UNITED STATES PATENT OFFICE.

STEPHEN DONNER, OF HASTINGS, MICHIGAN.

VEGETABLE-BLOCKING MACHINE.

Application filed January 17, 1925. Serial No. 3,102.

This invention relates to improvements in vegetable blocking machines.

In the raising of vegetables such as sugar beets, the seeds are sown with drills and it is necessary to thin the beets in the rows. This, so far as I am aware, has been done ordinarily by hand labor.

The main objects of this invention are:

First, to provide a machine which rapidly and effectively blocks the beets leaving the ground in proper condition for cultivation and further care of the crop with a minimum of labor.

Second, to provide a machine having these advantages in which the blade or tool is given a movement very similar to that imparted to a hoe by hand whereby substantially the minimum amount of soil is removed and is effectively discharged.

Third, to provide a machine having these advantages which is capable of ready adjustment to meet the various operating conditions, such as variation in soil, soil conditions and the like.

Objects pertaining to details and economies of construction and operation of my invention will definitely appear from the detailed description to follow.

I accomplish the objects of my invention by the devices and means described in the following specification. The invention is clearly defined and pointed out in the claims.

A structure embodying the features of my invention is clearly illustrated in the accompanying drawing forming a part of this application, in which:

Fig. I is a plan view of a structure embodying the features of my invention, only such parts of the machine being illustrated as are deemed necessary to properly illustrate my improvements.

Fig. II is a side elevation thereof.

Fig. III is a transverse section on a line corresponding to line 3—3 of Fig. I.

Fig. IV is a transverse section on a line corresponding to line 4—4 of Fig. I, the path of the edge of the tool in its stroke being indicated.

Fig. V is a sectional view through the tool or blade on a line corresponding to line 5—5 of Fig. IV.

In the drawing the sectional views are taken looking in the direction of the little arrows at the ends of the section lines and similar numerals of reference indicate similar parts in all of the views.

Referring to the drawing, I provide a main running gear frame designated generally by the numeral 1 and comprising suitable longitudinal sills 2 formed of angle iron and disposed with their angles facing inwardly and upwardly. The rear axle 3 is provided with wheels 4 and 5, the wheel 5 being a driving wheel and having a driving sleeve 6 thereon provided with beveled gears 7 disposed centrally of the frame. The front wheels 8 are mounted on an axle 9 connected to the frame by the king bolt 10.

I provide a sub-frame designated generally by the numeral 11 and comprising end members 12 and cross members 13 and 14. This frame is mounted between the side rails 2 for vertical movement, the blocks 15 supporting the frame against longitudinal movement. The top cross piece 16 on the sub-frame is connected to the arm 17 of the adjusting lever 18 by means of the link 19. A segment 20 is provided for adjustably supporting the lever. The lever is carried by cross pieces 46 disposed on the main frame at the rear of the sub-frame.

The sub-frame carries the tool supporting frame or carrier 21 which is supported at one end by the crank 22 on the main frame and at its other end by the oscillating supporting arm 23 which is pivotally mounted at 24 on the bracket 25 projecting from the main frame so that the carrier has a circular motion at one end and an oscillating motion at the other.

The blade or tool 26 is adjustably mounted on the carrier 21 below the crank by means of the pivot bolt 27 and the bolt 28 engaging the segmental slot 29 in the bracket 30 depending from the carrier 21. The crank 22 is a driven crank, the driving means in the embodiment illustrated comprising a driving shaft 31 connected to the driving pinion 32 meshing with the gear 27 by means of the clutch shown conventionally at 33. The clutch is controlled from the foot lever 34, see Fig. I. The shaft 31 is also provided with a brake shown conventionally at 35 and controlled from the foot lever 36.

The driving shaft is connected to the crank through the flexible connection consisting of the shaft section 37, universal joint 38 and a train of gears designated generally by the numeral 39. This train of gears is mounted on the sub-frame, the gear 40 of the train having a stub shaft section 41 connected to one member of the universal joint

38. The purpose of this train of gears is to properly time the movement of the carrier and in practice the gears 42 and 43 of the train are changed according to the speed at 5 which it is desired to drive the tool. Thus arranged the path of the tool is approximately as indicated in Fig. IV which provides for a forward movement in an approximately horizontal plane with an upwardly 10 lifting return movement which effectively discharges the soil and quite an abrupt down stroke which carries the tool into the soil at the beginning of the stroke.

In practice the machine is driven along a 15 row of beets or other vegetables to be "blocked", the blade or tool being of a width corresponding to the space which is desired between the vegetables. The speed of the tool carrier is adjusted to correspond to the 20 undisturbed space it is desired to leave between the strokes.

My improved blocking machine is highly 25 efficient and moves the soil in a manner which does not seriously disturb the plants left in the rows. The tool is preferably formed with side flanges 44 which cut along the edge of the tool rather than tearing the soil, which might disturb the plants, particularly where the soil is crusted.

30 The machine is preferably provided with cross bars 45 upon which cultivator units may be mounted. However, as these features form no part of my present invention I have not illustrated or described the same 35 herein.

I have illustrated and described my improvements in an embodiment which I deem 40 very practical. I have not attempted to illustrate or describe various adaptations or modifications as I believe the disclosure will enable those skilled in the art to embody or adapt the same as may be desired.

Having thus described my invention what 45 I claim as new and desire to secure by Letters Patent is:

1. In a machine of the class described, the 50 combination of a running gear frame, a sub-frame mounted on said running gear frame for vertical adjustment, means for adjusting said frame, a tool carrier having an upwardly projecting arm at its outer end, a crank on which the inner end of said tool carrier is mounted carried by said sub-frame, a link pivoted on said frame and 55 pivotally connected to said arm on said tool carrier for supporting the outer end of the carrier for oscillating movement in an upwardly curving arc, a tool mounted on said carrier below said crank, a train of gears 60 mounted on said sub-frame and operatively associated with said crank, a driving shaft mounted on said running gear frame and having a universal joint connection with said

train of gears, a driving clutch for said driving shaft, and a brake operatively associated 65 with said driving shaft.

2. In a machine of the class described, the combination of a running gear frame, a sub-frame mounted on said running gear frame for vertical adjustment, means for adjusting 70 said frame, a tool carrier, a crank on which the inner end of said tool carrier is mounted carried by said frame, means for oscillatingly supporting the outer end of said carrier whereby it is caused to move in an upwardly curving arc, a tool mounted on said carrier below said crank, a train of gears mounted on said sub-frame and operatively associated with said crank, a driving shaft mounted on said running gear frame and 75 having a universal joint connection with said train of gears, a driving clutch for said driving shaft, and a brake operatively associated with said driving shaft between the clutch and crank.

3. In a structure of the class described, the combination of a running gear frame, a sub-frame adjustably mounted on said running gear frame, means for adjusting said frame and supporting it in its adjusted positions, a tool carrier, a supporting crank for the inner end of said carrier, an oscillating supporting link for the outer end of said carrier, a tool mounted on said carrier, a driving shaft mounted on said running gear frame and operatively connected to said crank, a driving clutch for said driving shaft, and a brake operatively associated 90 with said driving shaft.

4. In a machine of the class described, the combination of a supporting frame, a horizontally disposed tool carrier having a tool mounted thereon towards one end, and means for supporting and driving said tool carrier comprising a revolving crank with connection near the tool whereby circular motion is imparted to one end of said carrier and a horizontally disposed link connection at the opposite end whereby an oscillating movement in an upwardly curving arc of a circle 100 is imparted to the other end.

5. In a machine of the class described, the combination of a supporting frame, a horizontally disposed tool carrier having a hoe-like cutter tool mounted toward one end, means for supporting and driving said tool carrier comprising a revolving crank with connection near the tool, and means for supporting the opposite end of said tool carrier to permit its oscillation in an upward direction to control the movement of the tool in a horizontal and upward cutting movement, 110 as specified.

In witness whereof I have hereunto set my hand.

STEPHEN DONNER.
